UNITED STATES PATENT OFFICE.

WILHELM MAIER, OF VILLINGEN, GERMANY.

DESIGN FOR A COMBINATION CLOCK AND MUSIC BOX.

61,419.

Specification for Design.

Patented Aug. 29, 1922.

Application filed April 5, 1922. Serial No. 1,556. Term of patent 14 years.

To all whom it may concern:

Be it known that I, WILHELM MAIER, a citizen of the German Republic, residing at Villingen, Germany, have invented a new, original, and ornamental Design for a Combination Clock and Music Box, of which the following is a specification.

The figure is a front elevational view showing my new original design. The upper part forming the clock frame proper is combined with a music box formed as a rectangular base. The latter is connected with the clock case by means of ornamental supports.

I claim:

The ornamental design for a combination clock frame and music box as shown and described.

In testimony whereof I have signed my name to this specification in the presence of two subscribing witnesses.

WILHELM MAIER.
